GUNWALE CLAMP FOR HOLDING FISHING RODS OR OARS

Lewis E. Hamel, Rochester, N. Y., assignor to Lewis E. Hempel Co., Inc., Rochester, N. Y., a corporation of New York

Application June 1, 1955, Serial No. 36,320

Term of patent 14 years

(Cl. D54—2)

FIG. 1.

FIG. 2.

FIG. 3.

FIG. 5.

FIG. 4.

Fig. 1 is a view in side elevation of a gunwale clamp for holding fishing rods or oars showing my new design;

Fig. 2 is a bottom plan view;

Fig. 3 is a top plan view;

Fig. 4 is an end elevation; and

Fig. 5 is an end elevation showing the end opposite Fig. 4.

I claim:

The ornamental design for a gunwale clamp for holding fishing rods or oars, as shown.

UNITED STATES PATENT OFFICE
CERTIFICATE OF CORRECTION

Patent No. 176,013

November 8, 1955

Lewis E. Hamel

It is hereby certified that error appears in the above numbered patent requiring correction and that the said Letters Patent should read as corrected below.

The name of the assignee was erroneously described and specified as "Lewis E. Hempel Co., Inc." whereas said name should have been described and specified as -- Lewis E. Hamel Co., Inc. --.

Signed and sealed this 13th day of December 1955.
